DESIGN FOR A HAND MIRROR FRAME

Joseph Casalino, Forest Hills Gardens, N. Y., assignor to Dieplast Corporation, New York, N. Y., a corporation of New York

Application October 19, 1944, Serial No. 115,860

Term of patent 3½ years

(Cl. D86—10)

To all whom it may concern:

Be it known that I, Joseph Casalino, a citizen of the United States, residing at Forest Hills Gardens, in the county of Queens and State of New York, have invented a new, original, and ornamental Design for Hand Mirror Frame, of which the following is a specification, reference being had to the accompanying drawing, forming a part thereof.

Fig. 1 is a front elevational view of a hand mirror frame showing my new design; Fig. 2 is a side view thereof; and Figs. 3 and 4 are sectional views on the lines 3—3 and 4—4, respectively, of Fig. 1.

I claim:

The ornamental design for a hand mirror frame, as shown.

JOSEPH CASALINO.
